Patented Apr. 24, 1928.

UNITED STATES PATENT OFFICE.

ANDREW J. FLEITER AND THEODORE A. MILLER, OF AKRON, OHIO, ASSIGNEES TO
THE AKRON STANDARD MOLD COMPANY, OF AKRON, OHIO, A CORPORATION OF
OHIO.

MOLD-ENGRAVING MACHINE.

Application filed March 30, 1926. Serial No. 98,477.

This invention relates to machines for engraving patterns in molds for the curing of rubber articles and particularly to the engraving of non-skid patterns in tire molds.

5 Although the invention is shown as applied to the engraving of pneumatic tire molds, it will be appreciated that the invention may be employed in the engraving of molds for other articles of a similar nature.

10 The objects of the invention and the advantages to be gained will be apparent to those skilled in this art. One of the primary objects of the invention is to provide an automatic mold engraving machine

15 which, when set in operation, will carry forward the engraving of the non-skid patterns without further attention on the part of the operator. The pattern is controlled by a series of cams, or similar devices, which

20 can be changed to suit the pattern desired to be cut in the mold. Each stage of the operation of the machine cuts a single unit or area of the pattern in the mold, and after the completion of the unit of the pattern the mold is advanced another step and a fresh pattern area is cut.

The machine provides a system of gearing and drive mechanism for accomplishing this result and, in addition, embodies an

30 accurate spacing mechanism so that the units of the pattern are reproduced at the required intervals about the mold.

The numerous advantages and benefits gained from the invention will be appreciated by a complete study of the invention as described herein. The machine, being entirely automatic, is cheaper to operate and gives better and more rapid production than prior machines.

40 The form of machine illustrated and described herein is one embodiment of the invention only. It will be understood that after the principles of the invention have been made clear to experienced and skilled persons in this art, it is possible to design other forms of machine for accomplishing similar results, which machines will embody specifically different mechanisms without departing from the essential features and principles of the invention as set forth herein and in the claims appended hereto.

50 In the drawings in which a preferred form of the invention is shown:

Figure 1 is a side elevation of the complete machine showing a pneumatic tire mold in section, mounted upon the rotating table or mold carriage; 55

Figure 2 is a sectional view through the center of the table for supporting the mold; 60

Figure 17 is a section on the line 17—17 of Figure 15; 135

Figures 18, 19 and 20 are details of the clutch which serves to intermittently connect the cam shaft with the drive shaft, 140
Figure 20 being a section on the line 20—20 of Figure 19; and 145

Figure 21 is a detail of the cam for reciprocating the head. 150

Briefly summarized, the operation of the machine is as follows: 155

The machine is designed especially for the cutting of the non-skid patterns in the tread of a tire mold, these parts being cut into the mold and being the reverse of the pattern on the completed tire. 160

In the drawings in which a preferred form of the invention is shown:

The tire mold is shown at 1, the tread thereof, or that portion to be cut away on this machine, is indicated at 2, the bottom of the recesses or cavities to be cut away by this machine being on an arc, the center of which is at the center of curvature of the tread portion of the tire. The cutting tool is indicated by the numeral 7.

The mold is carried upon a rotary turntable 8 which is given two distinct periods of movement about its axis, the first of which is a period of oscillation during which the tool is performing the cutting operation, the combined oscillation of the mold and movement of the tool radially of the mold causing the tool to travel over a path or series of strokes covering the complete area which is to be cut out in a single unit of the pattern. The second movement of the turntable accomplishes the spacing of the pattern units about the mold which takes place while the tool is inactive. During the second movement, the tool is clear of the mold.

The machine is mounted upon a bed plate 25 upon the upper surface of which at one side of the machine are located parallel guideways 11 upon which is slidably mounted the mold carriage 12. Centrally located on the under side of the mold carriage is a rack 13 which is engaged by a gear 14 mounted upon a transverse shaft 15 which is rotated in bearings in the bed plate. The outer end of the shaft 15 has secured to it by set screw 14^a a rocking arm 16, to the lower end of which is adjustably connected a long link 17, the adjustment being obtained by a plurality of holes 18 for the connection of the link, the holes being spaced at different distances from the shaft. The other end 40 of the link 17 is connected to a reciprocating slide 19 mounted on a horizontal guideway 20 at the side of the bed plate. The face of the slide 19 carries a roller 21 which travels in a track 22 on the inner face of a cam 23. The cam 23 is carried upon a continuously 45 rotating shaft 24 (Figure 14). It will be observed that this cam is of configuration to shift the mold carriage toward and from the center of the machine at regular intervals, the forward or outward position of the mold carriage being during the cutting operation and the inward position being during the period in which the mold is being moved to a new cutting position. In this manner 50 the tool may be freed from the mold so that the mold and tool can be shifted relatively to one another so as to advance to the next area without cutting into the metal.

If the pattern on the mold is such that the mold may be advanced without first shifting it with respect to the tool, the set screw 14^a is loosened and the shifting mechanism operates idly.

The turntable 8, upon which the mold is clamped, is mounted upon the carriage 12

by a pivot pin 5, the table resting upon friction reducing bearings and being rotated upon the axis of the mold by means of a large bevel gear 25 on the under side of the turntable. The gear 25 is in mesh with a 70 bevel pinion 26 formed upon an elongated sleeve 6 feathered upon the end of a horizontal shaft 27 (Figure 2). The end of the shaft is slidably received in a bearing 28 which is supported by arms 29 secured to 75 the under side of the sliding carriage 12. The bearing 28 holds the pinion 26 in mesh with the gear between the shoulder of the pinion and collars 30 on the end of the sleeve 6. Wear upon the feather is taken up by a 80 rotatable collar 31 fastened to the end of the bevel pinion by bolts 32 passing through slots 33 in the collar and into the pinion 26. The shaft 27 is permitted to move in and out with the movement of the mold carriage. 85

The shaft 27 imparts the two movements to the mold which were described above, a series of oscillations while the mold is at the outer extremity of its movement and while the cutting operation is going on, and the other a movement of advancement to a new cutting position which takes place while the mold is retracted or while the tool is inactive. The mechanism for rotating the shaft to obtain these movements at the proper time 95 will be described later.

From one side of the bed plate is erected the vertical standard 35, on one face of which is formed the vertical dovetail way 36 on which is engaged the vertically adjustable head 37, the position of adjustment being controlled by a vertical screw shaft 38. A crank 41 is received on the upper end of the screw shaft 38.

The head 37 extends over the mold and 105 serves as a support for the milling tool 7. The tool is secured in the bit 45 at the lower end of an elongated spindle 46, the upper end of the spindle being provided with a pulley 47 which is given a constant, rapid 110 rotation by any suitable flexible driving means. The spindle is mounted in a sleeve 48, which latter is adjustably mounted in housing 49 by means of a two-part clamping nut 50 adapted to be drawn together to 115 clamp the sleeve by means of a bolt 51. The sleeve and its tool are adjusted to the proper depth for cutting by means of a pinion 52 which engages a rack 53 cut into the side of the sleeve 48, the pinion being held in its 120 proper position by a set screw 54, the end of which is received in a groove 55 in the pinion. A squared end 56 on the gear affords a means for rotating the pinion.

The housing 49 is formed as a part of a 125 pivoted sector plate or tool carrier 60 which rocks upon a rearwardly projecting pin 61 which is received in a bushing 62 located in the lower part of the head 37. A thrust bearing 63 is located between the sector and 130

the head, and the bushing 62 is held in position by a nut 64. Pressure lubricating means for the pin of a well-known type is shown at 65.

- 5 To the rear of the sector plate is bolted a quadrant 66, the outer edge of which is formed with a rib 67 received and guided by an arc-shaped guide rail 68 which is secured to the head by a number of bolts 69.
- 10 To the outer periphery of the sector plate is secured a rack 70, which meshes with a horizontally reciprocating rack 71 secured to the outer end of a sliding bar 72. The rack is guided by a roller 100 received in a slot 101 in the rack, the roller being supported on a pin 102 in a bracket 103 carried on the head 37. The bar 72 is guided in a plate 73 mounted on the head 37 and is connected at its rear end to a plate 74 which is guided in horizontal guideways 75 secured to a bracket 76. The bracket 76 is carried on the rear of the vertically adjustable head 37 and passes over a vertical shaft 90 which is driven intermittently by mechanism to be described. The upper end of the shaft 90 is provided with a keyway 80 and over this shaft is slidably fitted and feathered a horizontal cam 82, the under face of which is provided with a cam track 83.
- 30 A roller 84 on the slide plate 74 is received in this cam.

The rotation of the shaft 90 and its cam controls the reciprocation or radial movement of the tool with respect to the mold.

- 35 The cam is operative only while the cutting operation is going on and is inoperative while the spacing of the mold takes place, the shaft being connected or disconnected from its driving means, to be described, at the proper intervals. During the cutting operations the mold is oscillated about its axis and the combined radial movement of the tool and oscillation of the mold will generate any desired pattern in the mold.

- 45 There are, therefore, two factors which govern the pattern to be cut in the mold. The first factor is the radial movement of the tool, which, in this machine, is a movement of oscillation, although a straight line movement may be adopted. This factor is controlled by the cam 82 through the mechanism which has been described in connection with the head. The second factor is controlled through the rotation of the bevel pinion 26 by mechanism which will be described. Any path may be given to the tool by requisite changes in the controlling mechanism and any pattern may be reproduced. The pattern shown in Figure 9 has been selected for the purposes of illustration herein, the path of the tool being illustrated in that figure. In this figure the top of the mold, or the parting line which is situated at the center of the tread, is on the left side, it being observed that the pattern which has

been selected for illustration is provided with a central groove 95, which is cut in the mold on the boring mill before the operations herein described take place. The presence of this groove in the mold makes unnecessary the shifting of the mold relative to the tool prior to the spacing operation, so it may be assumed that the set screw 14^a is loosened.

70 It is apparent that if the tool is held stationary and the mold is moved about its axis, a straight circumferential line will be cut in the mold. If the mold is held stationary and the tool moved radially a straight radial line will be formed. If the mold and tool are both moved, diagonal or curved lines of any pattern will be formed.

75 Taking the pattern of Figure 9 and tracing the radial periods of movement or rest of the tool by the cam of Figure 21, the following will be observed.

80 Assuming that the cutting tool is at the starting and stopping point Y, it will be observed that the cam roller 84 is shown at the corresponding point on the cam, which is at the outer limit of the cam so that the tool is at the position shown in Figures 1 and 4.

85 The first cut is along the line Y—A and is a diagonal cut so that the mold is moving downwardly, as viewed in Figure 9, while the tool is moved toward the axis of the mold by the cam surface Y—A on cam 82.

90 The diagonal cut A—B is then made by an outward movement of the tool, controlled by the cam surface A—B while the mold continues its downward movement. The circumferential line B—C is then generated while the tool is stationary and the mold continues its downward movement. The mold is then stationary while the radial line C—D is cut by a radial movement of the tool. The tool is then held stationary while the mold is moved downwardly to obtain the cut D—E. Combined movement of the mold and tool generate the next cut E—F and combined movement of the tool and reverse movement of the mold generate the line F—G. A stationary tool and an upwardly moving mold obtain the line G—H. The lines H—I and I—J are then cut in the same manner.

100 105 110 115 120 125 130

The cuts so far described have removed a path about the large recess of the pattern, leaving an island of metal in the center which has to be cut away. The cuts J—K, K—L, L—M, M—N, N—O and O—P remove this island. The first cut has been in the nature of a roughening-out cut and it is desirable at times to take a finishing cut around the figure, closely following the path of the first cut. After the movement P—Q, the tool is moved along the lines Q—R, R—S, S—T, T—U, U—V and V—W, and then out of the recess along the lines

135 140 145 150 155 160 165 170 175 180

W—X and X—Y to the starting point. When the tool reaches its starting point, the shaft 90 ceases to rotate and the spacing mechanism comes into play, moving the tool on to the next starting point Z.

If the pattern of the tire tread does not include the rib formed by the groove 95 the mold shifting mechanism, operating through the cam 23 and the gear 14 and rack 13, will shift the mold to the position shown in Figure 1 before the spacing mechanism comes into play, thus allowing the tool to clear the mold.

The mechanism for obtaining the oscillation of the mold during cutting and the feeding movement between cuts, or the spacing, will now be described.

The power for the machine is derived from a pulley 135 which is located at the side of the machine (Figure 11) and which carries a pinion 136 meshing with a pinion 137 which is secured upon a worm drive shaft 138 passing through the bed plate and supported at its inner end in a bracket 139. The worm 140 on the shaft 138 meshes with a worm gear 141 which is secured to the lower end of a vertical shaft 142, which is rotated continuously during the operation of the machine, being supported in a bearing 143 on a plate 144 which also supports the various driving elements for the mold.

The lower end of the shaft 142 carries a bevel pinion 145 which meshes with a bevel pinion 146 on the cam shaft 24, and drives the latter.

Shaft 142 is in direct alignment with the shaft 90, the latter having a reduced end 147 which has a step bearing in the upper end of the shaft 142.

Near its upper end the shaft 142 has a fixed gear 150 (Figures 18, 19 and 20), the upper end of which is cupped to receive a plate 151 which is provided with a radial dove-tailed guideway 152 extending from the shaft 142 to the edge of the plate 151. A sliding clutch pin 153 is movable in the guideway 152, being yieldingly forced outward by a spring 154 received at its inner end over a screw-threaded pin 155 on the shaft 142. A finger 156 on the clutch pin engages a notch 157 located on the inside of a disk 158 which is keyed to the lower end of the shaft 90. The tail 159 of the clutch pin projects outwardly beyond the disk and gear. When, therefore, the clutch pin projects outwardly, the shaft 142 and 90 are locked together and rotate simultaneously through the clutch which has just been described. When the clutch pin is forced inwardly, however, the two shafts are disconnected and the finger 156 rides around in retracted position on the inner circular wall 160 formed in the lower face of the disk 158. The shaft 90 is thus stationary until the pin is again brought in alignment with

the notch 157. By the mechanism which has just been described, the reciprocation of the tool carrier is rendered intermittent, the cutting operation taking place when the clutch is engaged and the spacing operation 70 taking place when the clutch is disengaged.

At this point, it may be stated that the term "reciprocation" has been applied to the movement of the tool carrier for the purpose of convenience only and covers both 85 straight line reciprocation and oscillation.

In order to secure the intermittent operation of the clutch of Figures 18 and 19, the tail of the clutch is pressed inwardly by means of a dog 165 which is secured to the 80 upper face of a gear 166 which meshes with the gear 150. The gear 166 constitutes a timing mechanism for the cam shaft 90 and has twice the number of teeth as the gear 150 so that it follows that the clutch has a 85 complete active and a complete inactive rotation for each rotation of the gear 166, the dog 165 always meeting the tail of the clutch pin after a complete rotation of the gear 166 and the period of rotation of the gear 166 is equally divided between the 90 period of cutting and spacing of the mold.

The gear 166 is rotated upon a vertical pin 167, the lower end of which is received in the plate 144 and the upper end in a 95 bracket 168 secured to the bed plate and overhanging the gear. In addition to controlling the reciprocation of the cutting head, the gear 166 controls the spacing of the mold during the non-cutting operation 100 by a heart-shaped cam 169 with which cooperates a clutch control cam 170.

The oscillation of the mold during the cutting operation is controlled by a cam 175 which is fastened to the lower end of the 105 shaft 90 and rotates only when the shaft rotates and then only while the tool is reciprocated over the mold by its cam 82. The detail of the cam 175 is shown in Figure 10 in which the various surfaces are marked 110 to correspond with the movements of the cutting tool as illustrated in Figure 9. Thus the surfaces Y—A, A—B, B—C, etc. give the required oscillation or dwell in the mold operating mechanism to enable the tool to 115 describe the required path in the unit of tread design.

Against the surface of the cam 175 bears a roller 176 which is carried on a plate 177 adjusted by bolt and slot connections 178 120 upon a slide 179 which reciprocates upon a dovetailed guideway 180 formed on the upper surface of a bridge piece 181 which is supported upon pillars 182 from the plate 144.

To the side of the slide 179 is attached an angular rack 183 having teeth on its underside which engage a pinion 184 freely rotatable on the shaft 27 and located between a collar 185 and the end of a long 130

sleeve 186 (Figure 15). Whenever the cam 175 is rotated, the gear 184 is rotated which will oscillate the mold table through the bevel gearing 25 and 26 on the shaft 27 through clutch mechanism to be described.

The shaft 27 extends through the machine and is supported through the medium of the sleeves about the shaft in a bearing 187. The sleeve 186 immediately surrounds the shaft 27 and is formed at its inner end with a flange 188 which is secured to the face of the gear 184. It extends along the shaft to a point outside the bearing 187, at which point the sleeve has keyed to it an arm 189 having a hub about which is rotatably mounted a short arm 190, the two arms being adjusted by means of arc-shaped slots 192 in the arm 190 and bolts 193 passing through the slots into the arm 189. On one side of the arm is carried an adjustable weight 194 which, acting through the sleeve 186, maintains the roller 176 in contact with the cam 175.

To the end of the shaft 27 is keyed a gear 195 which meshes with an idler gear 196 which is carried in a slot 197 on the adjustable arm 190. The gear 196 meshes with a pinion 198 on the end of a stub shaft 199 adjustably mounted in a slot 200 formed in the rocking arm 189 (Figure 16). The shaft 199 carries at its inner end a large gear 201 which meshes with a smaller gear 202 which is keyed to a sleeve 203, received within the bearing 187 (Figure 15). The gearing 202 to 195 constitutes an adjustable speed drive which can be altered as desired, the adjustable arm 190 permitting the mounting of varying gears in the train to obtain the required spacing of the pattern about the mold.

The flange 188 is provided with a notch 204 and the gear 184 with an aligned notch 214, and in these notches is adapted to enter a pin 205 projecting from the inner face of a sleeve 206, which is feathered upon the sleeve 203 by elongated keys 207. The sleeve 206 is shifted longitudinally upon the shaft 206 by means of a collar 208 which is engaged by the spanner arms 209 of a rocking lever 210 which is pivoted on the shaft 142. The lever 210 extends toward the cam 170 and the tail of the lever is forced against the edge of the cam by a spring 211. The arrangement of this cam is such that when the clutch between the shafts 90 and 142 is engaged, the pin 205 is engaged in the notches 204 and 214 so that the shaft 27 is oscillated by the cam 175 only during the reciprocation of the tool carrier. During the oscillation of the shaft 27 the adjustable differential gearing carried by the oscillating arms 189-190 is locked by the clutch 204-205.

The turntable is moved by the cam 169 attached to the gear 166, the cam track being engaged by a roller 215 which is carried

upon a rack 216 movable in the upper surface of the plate 144 and meshing with a gear 217 secured to a stub shaft 218 which is mounted in a housing 219. The shaft 218 carries a gear 220 which meshes with a pinion 221 on a second stub shaft 222 also mounted in the housing 219. The shaft 222 carries a gear 223 which meshes with a gear 224 loosely mounted on the sleeve 203. The gear 224 is slidable upon the sleeve 203, being provided with a groove 225 which is engaged by pins 226 on the end of the sliding sleeve 206 opposite the pins 205. The gear 224 is yieldingly held at its outward limit of movement by a coil spring 227 (Figure 15) so that it can yield slightly when it operates as a clutch between the gearing driven by the cam 169 and the shaft 27. For this purpose the side of the gear 224 is arranged with clutch teeth which are adapted to engage corresponding teeth on the face of a disk 228 which is keyed to the sleeve 203.

It will be observed that when the cam 175 is not rotated, at which time the clutch pin 205 is disengaged, the sleeve 203 is free to rotate, and it will be rotated when the clutch 224-228 is engaged, which position of the parts is illustrated in Figure 11. The movement of the rack 216 to space the mold table is then transmitted through the gearing 217 to 224 to the sleeve 203 and thence through the gear 202 and the reduction gearing on the arm 189 to the shaft 27. The feeding or spacing of the turntable takes place in alternation with its oscillation, the shifting of the sleeve 206 connecting or disconnecting the drive from the rack 216. The oscillation of the turntable is stopped and started by the operation of the clutch pin 153, which takes place at the proper time with the operation of the other parts of the machine.

It is believed that the operation of the machine will have been made clear by the description which has been given. The machine, having been set in motion, cuts a unit of the pattern and spaces each unit properly without any other attention on the part of the operator than to see that everything is working properly. The advantages in labor saving and the precision of the work are the principal advantages to be obtained. With appropriate changes in the various cams and adjustment of the parts, it is possible to obtain any desired pattern in the mold. The bodily shifting of the mold during the spacing is necessary only when the tool at its position of rest is within the figure on the mold. The arrangement of the cam 23 is such that it comes into operation at the termination of the cutting and before the advance or spacing movement takes place, a slight dwell being allowable at this point in the operation of the machine.

It will be apparent that the design of the machine shown herein will adapt itself to

multiple work, that is, to the connection of a series of machines to a common driving shaft so that the mold cutting may proceed on several molds at the same time.

5. It will be appreciated that the detailed construction of the machine is not necessary to the invention which may be embodied in other forms than that shown.

What is claimed is:

10. 1. In a machine for automatically cutting repetitions of a pattern in a tire mold, a turntable for supporting the mold, a cutter over the turntable, intermittently operative means to reciprocate the cutter and to oscillate the mold simultaneously, turntable rotating mechanism adapted to move the mold for the next pattern, and mechanism to cause the last named mechanism to operate during the pauses in the operation of the first named means.
15. 2. In a machine for automatically cutting repetitions of a pattern in a tire mold, a turntable for supporting the mold, a cutter over the turntable, rotary patterns operative jointly and intermittently to reciprocate the cutter and oscillate the mold, spacing mechanism for causing relative shifting of the mold and the cutter and means automatically operative to actuate the spacing mechanism only during the periods of dwell of the patterns.
20. 3. In a machine for automatically cutting repetitions of a pattern in a tire mold, a main shaft, a turntable for supporting the mold, a cutter movable over the turntable, a movable pattern for reciprocating the cutter and a movable pattern for oscillating the mold, mechanism driven from said shaft for moving the pattern, connections from said shaft for rotating the mold, and control devices for alternately moving the patterns and rotating the mold from the main shaft.
25. 4. In a machine for cutting tire molds, a turntable for supporting the mold, the turntable having two periods of operation, an oscillation and intermittent advance, a pattern to control the oscillation and driving mechanism for causing the advance, and a main shaft and means for connecting the main shaft with the turntable directly for the advance movement or through the pattern for the oscillation.
30. 5. In a machine for cutting tire molds, a turntable for supporting the mold, the turntable having two periods of operation, an oscillation and intermittent advance, a pattern to control the oscillation and driving mechanism for causing the advance, a main shaft and means for connecting the main shaft with the turntable directly for the advance movement or through the pattern for the oscillation, and a reciprocating tool operable during the period of mold oscillation.
35. 6. In a machine for cutting tire molds, a turntable for supporting the mold, the turn-

table having two periods of operation, an oscillation and intermittent advance, a pattern to control the oscillation and driving mechanism for causing the advance, a main shaft and means for connecting the main shaft with the turntable directly for the advance movement or through the pattern for the oscillation, and a reciprocating tool and a pattern therefor operable during the period of mold oscillation.

7. In a machine for the cutting of tire molds, a turntable for supporting a mold, a reciprocating cutter over the turntable, means to reciprocate the cutter, and means to oscillate the turntable, said means by their joint action reproducing a pattern in the mold, a shaft, means to cause intermittent rotation of the shaft in regular periods, two cams upon the shaft, connections from one of said cams to the cutter reciprocating means and from the other cam to the turntable oscillating means, and intermittently acting means to advance the mold automatically during the dwell in the rotation of the shaft.

8. In a machine for cutting tire molds, a turntable for supporting a mold, a reciprocating cutter over the turntable, means to reciprocate the cutter, and means to oscillate the turntable, said means by their joint action reproducing a pattern in the mold, intermittently rotated patterns to control the movement of cutter and the oscillation of the turntable, and means to advance the mold operable only during the dwell in the rotation of the patterns.

9. In a machine for cutting tire molds, a turntable for supporting a mold, a reciprocating cutter over the turntable, means to reciprocate the cutter, and means to oscillate the turntable, said means by their joint action reproducing a pattern in the mold, intermittently actuated patterns to control the movement of the cutter and the oscillation of the turntable, and means to advance the mold operable only during the dwell in the movement of the patterns.

10. In a machine for cutting tire molds, a turntable for supporting a mold, a reciprocating cutter over the turntable, means to reciprocate the cutter, and means to oscillate the turntable, said means by their joint action reproducing a pattern in the mold, intermittently actuated power operated means to control both of said movements, and means to shift the cutter and the mold to a new position during the periods of dwell of the power means.

11. In a machine for cutting tire molds, a turntable for supporting a mold, a reciprocating cutter over the turntable, means to reciprocate the cutter, and means to oscillate the turntable, said means by their joint action reproducing a pattern in the mold, a single power operated means to control

both of said movements at one period and to space the pattern about the mold at another period, and mechanism operating selectively to alternate the actions of said power operated means.

12. In a machine for cutting tire molds, a turntable for supporting a mold, a reciprocating cutter over the turntable, means to reciprocate the cutter, and means to oscillate the turntable, said means by their joint action reproducing a pattern in the mold, a power operated means to control both of said movements and to space the pattern about the mold, the spacing taking place alternately with the cutting of the pattern and clutch mechanism in the power means to effect the alternate control.

13. In a machine for cutting tire molds, a turntable, a pinion for driving the turntable, a shaft carrying said pinion, separate driving means for said shaft, one of said driving means adapted to move the shaft intermittently in one direction and the other driving means adapted to oscillate the shaft, and control mechanism for causing alternate action of the driving means.

14. In a machine for cutting tire molds, a turntable, a pinion for driving the turntable, a shaft carrying said pinion, separate driving means for said shaft, one of said driving means adapted to move the shaft intermittently in one direction and the other driving means adapted to oscillate the shaft, the said driving means acting alternately, and a cutter adapted to move over the mold during the operation of the second named driving means.

15. In a machine for cutting tire molds, a turntable, a pinion for driving the turntable, a shaft carrying said pinion, a cam, means for rotating the cam intermittently, driving connections for said shaft driven by the cam, a second cam, driving connections between the second cam and the shaft, and a shiftable clutch in the connections between the second cam and the shaft.

16. In a machine for cutting tire molds, a turntable, a pinion for driving the turntable, a shaft carrying said pinion, a cam, means for rotating the cam intermittently, driving connections for said shaft driven by the cam, a second cam, driving connections between the second cam and the shaft, and a shiftable clutch in the connections between the second cam and the shaft, the clutch being in engagement during the periods of dwell in the first named cam.

17. In a machine for cutting tire molds, a turntable, a pinion for driving the turntable, a shaft carrying said pinion, a cam, means for rotating the cam intermittently, driving connections for said shaft driven by the cam, a second cam, driving connections between the second cam and the shaft, a shiftable clutch in the connections between

the second cam and the shaft, the clutch being in engagement during the periods of dwell in the first named cam, and a cutter movable over the mold while the clutch is out of engagement.

18. In a machine for cutting tire molds, the combination of a turntable for the mold and a cutter movable radially of the mold, a shaft, a pattern on the shaft to control the movement of the cutter, a drive shaft, means to connect the pattern shaft to the drive shaft during a portion of the revolution of the latter, a connection between the drive shaft and the turntable, and a clutch in said connection maintained in operative relation while the pattern shaft is disconnected.

19. In a machine for cutting tire molds, the combination of a turntable for the mold and a cutter movable over the surface of the mold, a shaft, a pattern on the shaft to control the movement of the cutter, a drive shaft, means to connect the pattern shaft to the drive shaft during a portion of the revolution of the latter, and a connection between the drive shaft and the turntable operative only while the pattern shaft is disconnected.

20. In a machine for cutting tire molds, the combination of a turntable for the mold, a cutter, means to obtain active and inactive periods in the operation of the cutter, a single pattern for controlling the movement of the cutter during all of its active periods, a drive shaft for the turntable, and connections for actuating the drive shaft in one direction during the inactive periods of the cutter.

21. In a machine for cutting tire molds, the combination of a turntable for the mold, a cutter, means to obtain active and inactive periods in the operation of the cutter, a pattern for controlling the movement of the cutter during its active period, a drive shaft for the turntable, and connections for actuating the drive shaft in one direction during the inactive periods of the cutter and for oscillating the drive shaft during the active periods of the cutter.

22. In a machine for cutting tire molds, the combination of a turntable for the mold, a cutter, means to obtain timed active and inactive periods in the operation of the cutter, a pattern for controlling the movement of the cutter during its active period, a drive shaft for the turntable, and connections operative at timed intervals for oscillating the drive shaft during the active periods of the cutter only.

23. In a machine for cutting tire molds, a turntable, a drive for the turntable comprising a shaft, a gear secured to the shaft, a rack in mesh with the gear, a cam reciprocating the rack, means including a continuously driven power shaft and a periodically operative clutch mechanism associated with

- the power shaft for rotating the cam at intervals, and a cutting tool movable over the mold during the operation of the cam.
24. In a machine for cutting tire molds, a turntable, a drive for the turntable comprising a shaft, a gear secured to the shaft, a rack in mesh with the gear, a cam for reciprocating the rack, a second cam movable with the first said cam, means including a continuously driven power shaft and a periodically operative clutch mechanism associated with the power shaft for rotating the cams at intervals, and a cutting tool actuated by the second cam and movable over the mold.
25. In a machine for cutting tire molds, a turntable, a drive for the turntable comprising a shaft, means for rotating the shaft, a cam for controlling said means, a second cam movable with the first said cam, means including a continuously driven power shaft and a periodically operative clutch mechanism associated with the power shaft for rotating the cams at intervals, and a cutting tool actuated by the second cam and movable over the mold.
26. In a machine for cutting tire molds, a continuously rotating shaft, a cam rotated by the shaft, a turntable, a turntable rotating shaft, a cam shaft, a clutch between the first said shaft and the cam shaft, a timing mechanism adapted to render said clutch inactive at intervals, a second clutch on the turntable shaft, means actuated by the cam to throw the second clutch, and means to operate the turntable shaft from the cam shaft and from the cam alternately.
27. In a machine for cutting tire molds, a tool, means to reciprocate the tool over the surface of the mold and oscillate the mold during the cutting operation, and automatic means to shift the tool and the mold relatively at the end of the cutting operation so as to cause the tool to clear the mold.
28. In a machine for cutting tire molds, a tool, means to reciprocate the tool over the surface of the mold and oscillate the mold during the cutting operation, means operative in timed relation to shift the tool and the mold relatively at the end of the cutting operation so as to cause the tool to clear the mold, and means to advance the mold between cutting operations.
29. In a machine for cutting tire molds, a tool, means to move the tool over the surface of the mold during the cutting operation and means operating concurrently therewith for oscillating the mold, a sliding and rotating table for supporting the mold, means operative in timed relation to shift the table to cause the tool to clear the mold, and means to rotate the table after it is shifted.
30. In a machine for cutting tire molds, a tool, means to move the tool over the surface of the mold during the cutting opera-
- tion, a sliding carriage, a rotatable mold table on the carriage, means to shift the carriage to cause the tool to clear the mold comprising a continuously rotated cam, a gear rocked by the cam and a rack on the carriage engaged by the gear, and means for moving the table after the carriage is shifted.
31. In a machine for cutting tire molds, a tool, means to move the tool over the surface of the mold during the cutting operation, a sliding carriage, a rotatable mold table on the carriage, means to move the carriage to cause the axis of the mold to approach or recede from the tool, means to oscillate the table while at its outward position, and means to advance the table while at its inward position.
32. In a machine for cutting tire molds, a cutter head, means to cause said cutter head to have periods of reciprocation and periods of rest, a rotary mold table, and means to cause said table to oscillate or advance selectively during the said periods of reciprocation and rest, respectively.
33. In a machine for cutting tire molds, a cutter head, means to cause said cutter head to have periods of reciprocation and periods of rest, a rotary mold table, means to cause said table to oscillate or advance selectively during the said periods of reciprocation and rest, respectively, and means to shift the tool head and the mold relatively between said periods.
34. In a machine for cutting tire molds, a cutting tool and a rotary mold table, means to cause the tool to travel over an area of the mold in a plurality of strokes to remove the metal in such area, and means to automatically advance the tool to the next area in the mold, the tool clearing the mold during the intervals between the said areas.
35. In a machine for cutting tire molds, a reciprocating tool and an oscillating mold carrier, means to cause the said elements to move at fixed times so that the metal in a definite area of the mold is removed, and means to automatically advance the tool to the next area in the mold, the tool clearing the mold during the intervals between the said areas.
36. In a machine for cutting tire molds, a cutting tool and a rotary mold table, means to cause the tool to travel over an area of the mold in a plurality of strokes to remove the metal in such area, means to automatically advance the tool to the next area in the mold, and means to shift the mold and the tool before the advance occurs so that the tool clears the mold.
37. In a machine for cutting tire molds, a reciprocating tool and an oscillating mold carrier, means to cause the said elements to move at fixed times so that the metal in

a definite area of the mold is removed, means to automatically advance the tool to the next area in the mold, and means to shift the mold and the tool before the advance occurs so that the tool clears the mold.

38. In a machine for cutting tire molds, a tool which reciprocates radially of the mold, an oscillatory table for supporting the mold, cams for controlling the movements of the tool and the table whereby the tool will cut away a definite area of pattern in the mold, and means to advance the table after each area is cut away operative in timed relation to the operation of the cams.

39. A machine for automatically cutting repetitions of a pattern in work comprising a movable support for the work, a cutter, means for advancing the work and the cutter over definite distances at periodic intervals, and pattern controlled mechanism for oscillating the work and reciprocating the cutter during the intervals between the advancement of the work.

40. A machine for automatically cutting repetitions of a pattern in work comprising a support for the work having two periods of operation, namely, an oscillation and an intermittent advance, a pattern to control the oscillation and driving mechanism to cause the advance, a main shaft, means for connecting the main shaft with the support directly for advance movement, or through the pattern for oscillation, and a reciprocating tool operable during the period of oscillation.

and means for connecting the main shaft with the support directly for advance movement, or through the pattern for oscillation.

35

41. A machine for automatically cutting repetitions of a pattern in work comprising a support for the work having two periods of operation, namely, an oscillation and an intermittent advance, a pattern to control the oscillation and driving mechanism to cause the advance, a main shaft, means for connecting the main shaft with the support directly for advance movement, or through the pattern for oscillation, and a reciprocating tool operable during the period of oscillation.

42. A machine for automatically cutting repetitions of a pattern in work comprising a support for the work having two periods of operation, namely, an oscillation and an intermittent advance, a pattern to control the oscillation and driving mechanism to cause the advance, a main shaft, means for connecting the main shaft with the support directly for advance movement, or through the pattern for oscillation, and a reciprocating tool and a pattern therefor operable during the period of oscillation.
